UNITED STATES PATENT OFFICE.

WILLIAM A. DOBSON, OF BRIDGEPORT, CONNECTICUT, ASSIGNOR TO UNDERWOOD TYPEWRITER COMPANY, OF NEW YORK, N. Y., A CORPORATION OF DELAWARE.

TYPEWRITING MACHINE.

Application filed December 12, 1922. Serial No. 606,363.

To all whom it may concern:

Be it known that I, WILLIAM A. DOBSON, a citizen of the United States, residing in Bridgeport, in the county of Fairfield and State of Connecticut, have invented certain new and useful Improvements in Typewriting Machines, of which the following is a specification.

The present invention relates to a "silent" key-mechanism for typewriting machines; that is to say, to a mechanism by means of which a key may function to print a character and concomitantly to actuate a ribbon-vibrator, or to act on other mechanisms in typewriting machines, while nevertheless being silent in the respect that it is ineffective to cause letter-space movement of the platen relative to the printing point.

Often, particularly in certain languages, a letter or character should have a particular accent-mark printed directly above it, or should be underscored; and, if keys bearing such accent or other special characters are not disconnected from the letter-space mechanism, the carriage must be back-set after one key is operated, to permit both the letter and the accent key, for instance, to print at the same point in the line.

Silent-key-mechanism which obviates the necessity of such back-setting is not broadly new with the present invention. In the prior art, however, the silent-key-mechanism generally involves actuation of the universal bar or its equivalent, and consequently involves the presence and operation of some special device, such that the universal bar, although actuated, is nevertheless disabled to effect letter-space movement.

Even where the silent-key-lever has been disconnected from the universal bar, to be operable independently thereof, its connections to the ribbon-vibrator, to provide for a variable throw of the ribbon-vibrator for printing by the silent-key in any selected color zone of a bichrome ribbon, have not been entirely satisfactory.

An object of the invention is the provision of means, simple in construction and reliable in action, for actuating the ribbon-vibrator from the silent-key-lever, independently of the universal bar, such that the silent-key-characters may be printed through any selected color zone of a bichrome ribbon with the same facility as are

the characters of the letter and numeral keys.

It may happen that a single silent-key will not provide for all the desired characters in the nature of accent-characters; and, to meet this contingency, an object of the invention is the provision of additional silent-keys, and of means whereby, without operation of the universal bar, the ribbon-vibrator may be actuated from any selected one of a plurality of silent-keys, and a variable throw of the vibrator effected by the selected silent-key, for writing in any selected color zone of a bichrome ribbon.

Other features and advantages will hereinafter appear.

In the accompanying drawings,

Figure 1 is a perspective view of so much of an Underwood standard portable typewriter as involves the present invention.

Figure 2 is a top plan view of the draw-bar or link which connects the silent-key-lever to the intermediate ribbon-vibrator-lever.

Figure 3 is a top plan view of the intermediate ribbon-vibrator-lever.

Figure 4 is a top plan view, showing the connections of the silent-key, the ribbon color-control lever and the universal bar to the intermediate ribbon-vibrator-lever; the parts being in normal position and the color-control lever being set for the black ribbon-zone.

Figure 5 is a view similar to Figure 4, except that the color-control lever is set for the red ribbon-zone.

Figure 6 is a view similar to Figure 5, except that the parts are in the position assumed when the silent-key is depressed.

Character keys, one of which is shown at 15, when actuated, move key-levers 16 around a common fulcrum plate 17 supported on a cross-bar 18, extending between the sides 19 of the main frame. The key-lever 16, when actuated, moves against the tension of a spring 22 to swing a bell-crank, not shown, about a fulcrum 24 on a bracket 25 secured to a cross-bar 26, also extending between the sides 19 of the main frame. The bell-crank pulls on a link, not shown, to cause the types to strike against the front side of a platen 27.

The platen is journaled in a carriage 28, which may be urged from right to left in

the usual manner by a spring drum (not shown). To cause the carriage to move from one letter-space position to another, while typing, there is provided a universal bar 29 pivotally supported by means of arms 30 on a rock-shaft 31 and with which the key-levers engage, when depressed, by means of shoulders or lugs 32 on the key-levers. The rock-shaft 31 is journaled in brackets 33, one at each end thereof, secured to the cross-bar 18. An arm (not shown) on the universal bar connects with and operates escapement mechanism (not shown) for controlling the letter-feed movements of the carriage; so that, upon each depression of any letter or numeral key-lever, the carriage may have a letter-space advance under the action of the spring drum. Escapement mechanism suitable for this purpose is shown in United States Letters Patent to Dobson, No. 1,417,304, dated May 23, 1922.

At each type-stroke, a ribbon 34 is moved into the path of the striking type-bars. This movement of the ribbon is effected by an upwardly-extending crank 35 fast on the rock-shaft 31 of the universal bar. The crank 35, at the upper end thereof, carries a pin 36 to which is rotatably connected a strap 37 carrying an ear 38; the strap being held on the pin by the head 39 of the latter. Pivotally connected at 40 to the ear 38 is an arm 41, the forward end of which has a one-way connection at 42 with the intermediate or ribbon-vibrator-lever 43; that is to say, the arm 41 actuates the ribbon-vibrator-lever only in the forward movement of the crank 35. For reasons more fully to be hereinafter described, the one-way connection referred to permits the ribbon-vibrator-lever to be free to move forward without involving movement of the crank 35 or rock-shaft 31. The one-way connection of the arm 41 to the lever 43 is shown and described in the Dobson patent referred to. Briefly, the arm 41 has an enlarged part 44 terminating in shoulders 45, beyond which the arm is of reduced cross-section, as shown at 46. The reduced portion 46 is adapted to move freely in a threaded sleeve 47 on the intermediate lever. On forward movement of the crank arm 35 and the arm 41, the shoulders 45 of the arm 41, by engagement with the rear end of the sleeve 47, cause the intermediate lever to be rocked forward. When the intermediate lever is rocked forward other than by means of the arm 41, however, the sleeve 47 slides over the reduced portion 46 of the arm 41 without drawing on the latter to rock the crank arm 35. The connection between the arm 41 and the intermediate lever 43 is a shiftable connection, hereinafter more fully to be described, for varying the throw of the intermediate lever in setting the ribbon-vibrator 43 for the different color zones of the ribbon.

To permit of such shift, the sleeve 47 on the arm 41 carries on its under face a pin 41^a which projects into an arcuate slot 48 in the intermediate lever. A washer 49, see Figure 1, secured to this pin below the intermediate lever prevents upward displacement of the pin in the slot 48. The slot 48 is curved on a radius struck from the pivot 50 of the pivotal connection of the arm 41 to the ear 38 on the crank arm 35, so that the arm 41 may be swung from one to the other end of the slot 48 in the intermediate lever.

The intermediate lever is pivotally mounted on a stud 51 threaded into and secured to a bridge 52, which connects the cross-pieces 18 and 26. In order that the intermediate lever may not have up-and-down angular play, it is of U-shaped formation at the right-hand side; comprising two parallel arms; to wit, an upper arm 54 and a lower arm 55 connected by a vertical piece 56; the arms 54 and 55 being spaced well apart, and the stud 51 passing through both of these arms. The portion of the lever having the slot 48 is unitary with the upper arm 54; and the vertical part 56 of the lever carries vertical, elongated, rearwardly-directed parallel ears 57 for receiving therebetween a stud or pin 58 on a lever which forms an element of the ribbon-vibrator mechanism.

The last-named lever is a bell-crank lever pivoted at 59 to a rail or cross-piece 60 forming part of the platen-shift frame. This lever has a depending, substantially vertical arm 61 which carries the pin 58, by means of which the lever is actuated from the intermediate or ribbon-vibrator lever 43. Another arm 62 extends substantially horizontally leftward and terminates in a yoke 63, in which is engaged a pin 64 on the ribbon-vibrator 65. It follows from the foregoing that the forward swing of the intermediate lever 43 by the crank arm 35 on the universal bar or rock-shaft 31 results in a clockwise swing of the arm 61 and an upward movement of the arm 62, thereby actuating the ribbon-vibrator. The latter is provided with eyelets 66, through which the ribbon is threaded and is guided by ears 67 on parallel arms 68 of a vibrator-guide suitably secured to the shift-frame rail 60.

The carriage 28 has its movements in letter-feed and return directions on the shift-frame; the rail 60 serving as a runway support for the forward portion of the carriage, and there being a similar runway support for the rear of the carriage (not shown). By means not shown in the drawings of the present application, but which are fully shown in United States Letters Patent to Dobson, No. 1,335,956, dated April 6, 1920, the case-shift frame, with the carriage thereon, is adapted to be shifted upward on the main frame from lower-case

position to either a middle-case or an upper-case position; and suitable stops for determining these case positions are provided. Since the ribbon-vibrator and the ribbon-vibrator-lever are both secured to the cross-rail 60 of the shift-frame, these elements participate in the case-shift movements of the shift-frame. The intermediate or ribbon-vibrator-lever 43 is, however, mounted on the main frame and has no case-shift movement. It is to allow for the case-shift movement of the arm 61 and pin 58 thereon, with respect to the intermediate lever 43, that the elongated ears 57 on the intermediate lever are provided. These ears, with the pin 58, form a pin-and-slot connection between the arm 61 and the ribbon-vibrator lever 43; and this connection is maintained whatever the case position of the case-shift frame.

The ribbon is shown as having two color zones, to wit, an upper black zone 69 and a lower red zone 70. It follows that a greater throw of the ribbon-vibrator is required for printing in the red zone than for printing in the black zone. To obtain the desired variation in throw of the ribbon-vibrator, the setting of the connection of the crank arm 35 to the intermediate lever 43 is changed by means of a color-control lever 71. This lever, pivoted at 72 to a bracket 73 on the main frame, carries on its forward end a finger-piece 74, and at its rear end is connected by a link 75 to the arm 41, which connects the crank arm 35 to the intermediate or ribbon-vibrator-lever.

In Figure 4 the finger-piece 74 is shown in its extreme right-hand position, with the link 75 and the arm 41 in their extreme left-hand positions, as determined by the left-hand end of the slot 48 of the intermediate lever. In Figure 5 the finger-piece 74 is shown in its extreme left-hand position with the link 75 and the arm 41 in their extreme right-hand positions, as determined by the right-hand end of the slot 48. Since in Figure 5 the point of connection of the arm 41 to the intermediate lever is nearer the pivot 51 of the latter than it is in Figure 4, actuation of the universal bar will result in a greater throw of the ribbon-vibrator with the Figure 5 setting than with the Figure 4 setting. The finger-piece 74 may, however, be set at a point intermediate its Figure 4 and Figure 5 positions, in which event the arm 41 will register with the central portion of the slot 48 in the intermediate lever. It will be noted that the slot is enlarged at its center. This enlargement is sufficient to permit of movement of the crank arm 35 with the arm 41 without effecting movement of the intermediate lever. The central position is the so-called neutral position, in which the universal bar may be operated without operation of the

ribbon-vibrator. For convenience, a color plate 76 is fixed to the front plate 77 of the machine above the finger-piece 74 of the color-control lever. This color plate shows three color sections, to wit, a black section 78, a white or neutral section 79 and a red section 80, and the ribbon will print black, red or not at all, according as the finger-piece is set over one or the other of these color sections. The ribbon-vibrator-lever is returned to normal position after each actuation thereof by means of a coil spring 81 on the pivot stud 51. This spring is connected at one end to the bridge 52, on which the stud 51 is secured, and at its other end to the intermediate lever 43.

A silent-key 83 is carried by a lever 84 fulcrumed, as in the case of the letter and numeral key-levers 16, on the plate 17, and having a coil spring 22^a for returning the same to normal position. Since one or another of the characters 85 on the silent-key 83 is to be written directly over or under a previously written letter, letter-feed movement of the carriage is not desired when the silent-key is operated, and so the silent-key-lever 84 is not provided with the shoulder or lug 32 for operating the universal bar 29. No actuation of the crank arm 35 on the universal bar or rock-shaft 31 therefore takes place upon depression of the silent-key. As in the case of the other keys, however, it is necessary to operate the ribbon-vibrator by the silent-key; and for this purpose the following means are provided.

The silent-key-lever 84 has an arm 86 projecting upward therefrom. This arm is adapted to engage a roller 87 journaled in an ear 88 of a bracket 89 on a slide or link 90, and to cause the slide 90 to be pushed forward when the silent-key is depressed. The slide 90, at its forward end, is supported on a bracket 91 on the front plate 92 of the machine; and the forward end of the slide is set within and guided in a slot in the bracket 91. At its rear the slide 90 is guided by means of a yoke 93 thereon, which embraces the stud or pivot 51 of the intermediate lever. The slot 94 formed in the yoke permits forward and rearward movement of the slide relative to the stud 51. At its rear the slide also connects to and forms part of a plate 95 having a slot 96 therein similar to the slot 48 in the intermediate lever. The plate 95 lies flat upon the intermediate lever in such manner that, in the Figures 4 and 5 positions of the parts, that is to say, the position of the parts assumed when the silent-key is not operated, the slot 96 in the plate 95 registers with the slot 48 in the intermediate lever. The presence of the slide and plate therefore in nowise affects the movement of the link 75 and the arm 41 when the silent-key is not operated. The pin 41^a, which is carried by the arm 41 and

which passes through the slot 48 in the lever 43, also passes through the slot 96 in plate 95; so that when, as indicated in Figure 6, the slide 90 is drawn forward upon depression of the silent-key, the plate 95, through the pin 41^a, causes the intermediate lever 43 to be rocked around its pivot 51, thereby actuating the ribbon-vibrator in the manner hereinbefore described. In Figure 6 the pin 10 41^a is shown at the right-hand end of the slots 48 and 96, as determined by the position of the finger-piece 74 of the color-control lever over the red section 80 of the indicator plate, for printing of the silent-key 15 character through the red zone of the ribbon. It is obvious, however, that if, when the parts are in the Figure 4 position, for printing on the black ribbon-zone, the silent-key be operated, the slide 90 will rock the intermediate lever; although, as hereinbefore pointed out, the same movement of the slide, in this instance, will effect a shorter throw of the intermediate lever than when the color-control lever is in the Figure 6 position. 20

It may be desired to have more silent-key characters than can be taken care of by one silent-key. In this event two or more silent-key-levers may be employed. In Figure 2 25 two silent key-levers 84 and 97 are shown. The lever 97 is in all respects constructed and operated like the lever 84. A second bracket 98, somewhat similar to the bracket 89 is, however, secured to the under face of 30 the link or slide 90; and this bracket, like the bracket 89, carries a roller 99 for engagement with the upright arm 86 of the silent-key-lever 97. Operation of the lever 97 therefore results in the same movement of 35 the slide 90 as is effected by means of the lever 84. The brackets 89 and 98 are secured to the slide 90 by means of screws 100, which are passed through slots 101 in the slide and which thread into the brackets. The slots 40 101 permit of adjustment of the position of the rolls 87 and 99, so that in assembling the machine the rolls may be properly set with respect to the upright arms 86 on the silent key-levers. By means of other rolls 45 50 similar to rolls 87 and 99, on the slide 90, additional silent-key-levers may be made to operate the slide or link.

Variations may be resorted to within the scope of the invention, and portions of the 55 improvements may be used without others.

Having thus described my invention, I claim:

1. In a typewriting machine, a platen, a platen-carriage, mechanism for effecting a 60 letter-feed of the carriage, a universal bar for controlling the letter-feed mechanism, type-operating levers, means for operating the universal bar from the type-operating levers, a ribbon-vibrator, a lever for effecting a variable throw of the ribbon-vibrator 65

to present to the printing point the selected color-zone of a bichrome ribbon, said lever including an arcuate slot, means for operating the ribbon-vibrator-lever from the universal bar, an accent or silent-key-lever non-operative upon the universal bar, and means for operating the ribbon-vibrator from the accent or silent-key-lever independently of the universal bar, said last-mentioned means comprising a link overlying the ribbon-vibrator-lever, and moving idly therewith during actuation of the type-operating levers, a shoulder on the link, a finger on the silent-key-lever for engagement with the shoulder to actuate the link, said link having a slot in registry with said slot of the variable-throw lever, a pin passing through the slot of each of the overlying parts to connect the same for movement as a unit, and means for shifting the pin along said slots to change the point of connection of the link to the ribbon-vibrator-lever, to vary the throw of the latter. 70 75 80 85

2. In a typewriting machine, a platen, a platen-carriage, mechanism for effecting a letter-feed of the carriage, a universal bar for controlling the letter-feed mechanism, a type-operating levers, means for operating the universal bar from the type-operating levers, a ribbon-vibrator, a lever for effecting a variable throw of the ribbon-vibrator to present to the printing point the selected color-zone of a bichrome ribbon, means for operating the ribbon-vibrator-lever from the universal bar, and accent or silent-key-lever 90 non-operative upon the universal bar, and means for operating the ribbon-vibrator from the accent or silent-key-lever independently of the universal bar, said last-mentioned means comprising a floating link 95 positively connected to the ribbon-vibrator-lever, and moving idly therewith during actuation of the type-operating levers, a shoulder on the link, a finger on the accent or silent-key-lever for wiping engagement 100 with the shoulder, and means for changing the point of positive connection of the link to the ribbon-vibrator-lever to vary the throw of the latter. 105 110 115

3. In a typewriting machine, a platen, a platen-carriage, mechanism for effecting a letter-feed of the carriage, a universal bar for controlling the letter-feed mechanism, type-operating levers, means for operating the universal bar from the type-operating levers, a ribbon-vibrator, a lever for effecting a variable throw of the ribbon-vibrator to present to the printing point the selected color-zone of a bichrome ribbon, means for operating the ribbon-vibrator-lever from the universal bar, an accent or silent-key-lever 120 non-operative upon the universal bar, and means for operating the ribbon-vibrator from the accent or silent-key-lever independently of the universal bar, comprising a 125 130

- link positively connected to the ribbon-vibrator-lever, a roller on the link, a finger on the accent or silent-key-lever for wiping engagement with the roller, and means for changing the point of positive connection of the link to the ribbon-vibrator-lever to vary the throw of the latter.
4. In a typewriting machine, a platen, a platen-carriage, mechanism for effecting a letter-feed of the carriage, a universal bar for controlling the letter-feed mechanism, type-operating levers, means for operating the universal bar from the type-operating levers, a ribbon-vibrator, a lever for effecting a variable throw of the ribbon-vibrator to present to the printing point the selected color-zone of a bichrome ribbon, means for operating the ribbon-vibrator-lever from the universal bar, an accent or silent-key-lever non-operative upon the universal bar, and means for operating the ribbon-vibrator from the accent or silent-key-lever independently of the universal bar, comprising a link positively connected to the ribbon-vibrator-lever, a shoulder on the link, a finger on the accent or silent-key-lever for engagement with the shoulder, means for adjusting the position of the shoulder on the link, and means for changing the point of positive connection of the link to the ribbon-vibrator-lever to vary the throw of the latter.
5. In a typewriting machine, a platen, a platen-carriage, mechanism for effecting a letter-feed of the carriage, a universal bar for controlling the letter-feed mechanism, type-operating levers, means for operating the universal bar from the type-operating levers, a ribbon-vibrator, a lever for effecting a variable throw of the ribbon-vibrator to present to the printing point the selected color-zone of a bichrome ribbon, means for operating the ribbon-vibrator-lever from the universal bar, an accent or silent-key-lever non-operative upon the universal bar, and means for operating the ribbon-vibrator from the accent or silent-key-lever independently of the universal bar, said last-mentioned means comprising a floating link positively connected to the ribbon-vibrator-lever, and moving idly therewith during actuation of the type-operating levers, means on the accent or silent-key-lever for actuating said floating link, and means for changing the point of positive connection of said link to the ribbon-vibrator-lever, with respect to the pivot of said ribbon-vibrator-lever, to vary the throw of the latter.
6. In a typewriting machine, a platen, a platen-carriage, mechanism for effecting a letter-feed of the carriage, a universal bar for controlling the letter-feed mechanism, type-operating levers, means for operating the universal bar from the type-operating levers, a ribbon-vibrator, a lever for effecting a variable throw of the ribbon-vibrator to present to the printing point the selected color-zone of a bichrome ribbon, means for operating the ribbon-vibrator-lever from the universal bar, an accent or silent-key-lever non-operative upon the universal bar, and means for operating the ribbon-vibrator from the accent or silent-key-lever independently of the universal bar, comprising a floating link positively connected to the ribbon-vibrator-lever, and moving idly therewith during actuation of the type-operating levers, means on the accent or silent-key-lever for actuating the link, and means for shifting the link along the pivot of said ribbon-vibrator-lever, to vary the throw of the latter.
7. In a typewriting machine, a platen, a platen-carriage, mechanism for effecting a letter-feed of the carriage, a universal bar for controlling the letter-feed mechanism, type-operating levers, means for operating the universal bar from the type-operating levers, a ribbon-vibrator, a lever for effecting a variable throw of the ribbon-vibrator to present to the printing point the selected color-zone of a bichrome ribbon, means for operating the ribbon-vibrator-lever from the universal bar, an accent or silent-key-lever non-operative upon the universal bar, and means for operating the ribbon-vibrator from the accent or silent-key-lever independently of the universal bar, comprising a link positively connected to, and in part overlying, the ribbon-vibrator-lever, said overlying parts being slotted outwardly with respect to the pivot of the ribbon-vibrator-lever; a pin passing through the slots of both of said overlying parts to lock the same for movement together, means on the accent or silent-key-lever for actuating the link, and means for shifting the pin along said slots to change the point of connection of the link to the ribbon-vibrator-lever, for varying the throw of the latter.
8. In a typewriting machine, a platen, a platen-carriage, mechanism for effecting a letter-feed of the carriage, a universal bar for controlling the letter-head mechanism, type-operating levers, means for operating the universal bar from the type-operating levers, a ribbon-vibrator, a lever for effecting a variable throw of the ribbon-vibrator to present to the printing point the selected color-zone of a bichrome ribbon, means for operating the ribbon-vibrator-lever from the universal bar, an accent or silent-key-lever non-operative upon the universal bar, and means for operating the ribbon-vibrator from the accent or silent-key-lever independently of the universal bar, comprising a floating link positively connected to the ribbon-vibrator-lever, and moving idly therewith during actuation of the type-operating levers, means on the accent or silent-key-lever for actuating the link, and means for shifting the link along the pivot of said ribbon-vibrator-lever, to vary the throw of the latter.

pendently of the universal bar, comprising a link positively connected to, and in part overlying, the ribbon-vibrator-lever, said overlying parts being slotted outwardly with respect to the pivot of the ribbon-vibrator-lever; a pin passing through the slots of both of said overlying parts to lock the same for movement together, means on the accent or silent-key-lever for actuating the link, an arm carrying said pin, and a lever connected to the pin-carrying arm to move the same to shift the pin along said slots to change the point of connection of the link to the ribbon-vibrator-lever, for varying the throw of the latter.

9. In a typewriting machine, a platen, a platen-carriage, mechanism for effecting a letter-feed of the carriage, a universal bar for controlling the letter-feed mechanism, type-operating levers, means for operating the universal bar from the type-operating levers, a ribbon-vibrator, a lever for effecting a variable throw of the ribbon-vibrator to present to the printing point the selected color-zone of a bichrome ribbon, means for operating the ribbon-vibrator-lever from the universal bar, an accent or silent-key-lever non-operative upon said universal bar, and means for operating the ribbon-vibrator from the accent or silent-key-lever independently of the universal bar, comprising a link positively connected to, and in part overlying, the ribbon-vibrator-lever, said overlying parts being slotted outwardly with respect to the pivot of the ribbon-vibrator-lever; a pin passing through the slots of both of said overlying parts to lock the same for movement together, means on the accent or silent-key-lever for actuating the link, an arm carrying said pin, and a lever connected to the pin-carrying arm to move the same to shift the pin along said slots to change the point of connection of the link to the ribbon-vibrator-lever, for varying the throw of the latter; said pin-carrying arm being connected to the universal bar and having a one-way slip-connection with said pin, whereby the arm and pin thereon may move with the universal bar to actuate the ribbon-vibrator-lever, while nevertheless permitting the pin to be moved by the link from the accent or silent-key-lever without actuation of the universal bar.

10. In a typewriting machine, a platen, a platen-carriage, mechanism for effecting a letter-feed of the carriage, a universal bar for controlling the letter-feed mechanism, type-operating levers, means for operating the universal bar from the type-operating levers, a ribbon-vibrator, a lever for effecting a variable throw of the ribbon-vibrator, to present to the printing point the selected color-zone of a bichrome ribbon, means for operating the ribbon-vibrator-lever from the universal bar, an accent or

silent-key-lever non-operative upon said universal bar, and means for operating the ribbon-vibrator from the accent or silent-key-lever independently of the universal bar, comprising a link positively connected to, and in part overlying, the ribbon-vibrator-lever, said overlying parts being slotted outwardly with respect to the pivot of the ribbon-vibrator-lever; a pin passing through the slot of both of said overlying parts to lock the same for movement together, means on the accent or silent-key-lever for actuating the link, and means for shifting the pin along said slots to change the point of connection of the link to the ribbon-vibrator-lever, for varying the throw of the latter; said slots being enlarged at a part thereof to which the pin may be thrown for movement of the pin by the link from the accent or silent-key-lever without movement of the ribbon-vibrator-lever.

11. In a typewriting machine, a platen, a platen-carriage, mechanism for effecting a letter-feed of the carriage, a universal bar for controlling the letter-feed mechanism, type-operating levers, means for operating the universal bar from the type-operating levers, a ribbon-vibrator, a lever for effecting a variable throw of the ribbon-vibrator to present to the printing point the selected color-zone of a bichrome ribbon, means for operating the ribbon-vibrator-lever from the universal bar, a plurality of accent or silent-key-levers non-operative upon said universal bar, and means for operating the ribbon-vibrator from either of the accent or silent-key-levers independently of the universal bar, comprising a link positively connected to the ribbon-vibrator-lever, rollers on the link, a finger on each of the accent or silent-key-levers for wiping engagement with one of the rollers, and means for changing the point of positive connection of the link to the ribbon-vibrator-lever to vary the throw of the latter.

12. In a typewriting machine, a platen, a platen-carriage, mechanism for effecting a letter-feed of the carriage, a universal bar for controlling the letter-feed mechanism, type-operating levers, means for operating the universal bar from the type-operating levers, a ribbon-vibrator, a lever for effecting a variable throw of the ribbon-vibrator to present to the printing point the selected color-zone of a bichrome ribbon, means for operating the ribbon-vibrator-lever from the universal bar, a plurality of accent or silent-key-levers non-operative upon the universal bar, and means for operating the ribbon-vibrator from either of the accent or silent-key-levers independently of the universal bar, comprising a link positively connected to the ribbon-vibrator-lever, rollers on the link, a finger on each of the accent or silent-key-levers for wiping engagement

with one of the rollers, means for adjusting the position of the rollers, independently of each other, on the link, and means for changing the point of positive connection of the link to the ribbon-vibrator-lever to vary the throw of the latter.

13. In a typewriting machine having a letter-feeding carriage, type-operating keys, a universal bar operated by said keys and controlling the carriage, ribbon-vibrating mechanism operable by said universal bar, bichrome mechanism settable for different throws of the ribbon-vibrator, a silent key non-operative upon the universal bar, and means for enabling said silent key to operate said ribbon-vibrator at the different positions to which said bichrome mechanism is set, said vibrating mechanism including a lever operable by said universal bar, a link connected to move idly with said lever during the operation of said type-operating keys, and means to enable the silent key to actuate said link and thereby operate said lever to vibrate the ribbon.

25 14. In a typewriting machine having a letter-feeding carriage, type-operating keys, a universal bar operated by said keys and controlling the carriage, ribbon-vibrating mechanism operable by said universal bar,

bichrome mechanism settable for different 30 throws of the ribbon-vibrator, a silent key non-operative upon the universal bar, and means for enabling said silent key to operate said ribbon-vibrator at the different positions to which said bichrome mechanism is 35 set, said vibrating mechanism including a lever operable by said universal bar, a link connected to move idly with said lever during the operation of said type-operating keys, and means to enable the silent key to 40 actuate said link and thereby operate said lever to vibrate the ribbon at all positions to which the bichrome mechanism is set.

15. In a typewriting machine having a letter-feeding carriage, type-operating keys, 45 a universal bar operated by said keys and controlling the carriage, ribbon-vibrating mechanism including a lever operable by said universal bar, a link connected to move idly with said lever during the operation of 50 said type-operating keys, said link having a plurality of individually-adjustable shoulders, and a plurality of silent keys, each including a finger arranged to press against one of said adjustable shoulders to actuate 55 the link and thereby operate said lever to vibrate the ribbon.

WILLIAM A. DOBSON.
